UNITED STATES PATENT OFFICE.

LAWSON B. STEWART, OF RIMERSBURG, PENNSYLVANIA.

ROUNDABOUT.

1,014,346.

Specification of Letters Patent.

Patented Jan. 9, 1912.

Application filed February 11, 1911. Serial No. 608,093.

To all whom it may concern:

Be it known that I, LAWSON B. STEWART, a citizen of the United States, residing at Rimersburg, in the county of Clarion and 5 State of Pennsylvania, have invented certain new and useful Improvements in Roundabouts, of which the following is a specification, reference being had to the accompanying drawings.

10 My invention relates to new and useful improvements in toys, and more particularly to the class known as roundabouts, and my object is to provide a device of this character, which may be easily set up in 15 the home, or on the surrounding campus.

A still further object is to provide a device of this character which will accommodate several persons, and which may be easily operated by children.

20 A further object is to provide means for the operation of the device which may be manipulated by those using the same.

A further object is to provide an improved means of propulsion for the device, 25 and a still further object is to provide a revolving frame which is driven forwardly by means of clamps engaging a friction disk operated from seats on the frame.

With these and other objects in view, 30 my invention consists in the novel features of construction, combination and arrangements of parts as will be hereinafter referred to and more particularly pointed out in the specification and claims.

35 In the accompanying drawings forming a part of this application, Figure 1 is a perspective view of the device; Fig. 2 is a vertical section through the device as seen on line 2—2, Fig. 1; Fig. 3 is a top plan view 40 of the leverage connecting the operating handles with the clamping members; Fig. 4 is a detail perspective of one of the clamping members removed from its operative position; and Fig. 5 is a similar view of the 45 friction disk employed in my device.

In carrying out my invention I shall refer to the drawings in which similar reference characters designate corresponding parts throughout the several views, and in 50 which 1 indicates a base, which is adapted to be fixed to a floor, ground or the like,

by inserting stakes or the like through members 2 at the ends of said base, and extending upwardly therefrom is a mast or center pole 3, which is securely held in position 55 by means of the braces 4.

A frame composed of the head piece or sleeve 5, the radial arms 6 and braces 7 extending from the head piece to the arms, is revolubly mounted upon said mast by 60 providing said mast adjacent its upper end with a shoulder 8 upon which the lower face of said sleeve 5 rests after having received the upper end of said mast, and, by providing said mast adjacent its lower end 65 with an additional shoulder or collar 9, upon which is adapted to rest the lower faces of the radial arms 6. The inner ends of the radial arms 6 are secured to the bottom face of a circular plate 10, which plate 70 is provided with an opening 11 for the insertion therethrough of the mast 3, and mounted upon the outer ends of said arms are seats 12. As so described, it will be seen that the frame with the seats thereon is 75 adapted to revolve on the mast or center pole, and to propel the device from the seats on the frame, I provide my improved means which will be hereinafter described.

A metal friction disk 13, having a collar 80 14 thereon, is mounted upon the mast 3, a short distance above the plate 10 so as to be non-rotatable thereon, said disk being provided with a depending annular flange 15. A pair of clamping members 16, which 85 rest upon the upper face of the plate 10, are provided with slots 17 which receive the annular depending flange 15 of the disk 13, and the inner ends of said members are provided with integral shanks 18, disposed 90 along one side edge of the same, and engaging the central pole or mast 3. The plates 19 are secured at one end to the upper face of the members 16, and extend a short distance over the upper face of the 95 disk 13, thereby securely retaining said members in position on said disk. The outer ends of said members are split, as at 20, to receive the reduced ends of the links or pitmen 21, the opposite ends of said links being engaged with one end of L-shaped levers 22. These levers 22 are mounted on the sup-

ports 23 carried adjacent the ends of the arms 6, and the free ends of said levers are provided with handles 24 positioned adjacent the seats so that the occupants thereof may easily grasp the same.

It will be seen that by having the occupant in any one of the seats draw inwardly, or toward said seat, the handle 24, the clamp linked to that particular handle will be 10 swung in an arc so that the portion 25 of the outer wall of the slot 17 will be forced into frictional engagement with the outer face of the flange 15 of the friction disk, thereby causing the frame to revolve for- 15 wardly about said mast. The bearing face of the outer wall of said slot 17 is provided with a friction reënforcing face 25, and the point which is adapted to engage the disk when said clamp is moved in an arc, as de- 20 scribed, may be provided with serrations, and as it is essential to the propulsion of the device that the clamps be engaged with the friction disk alternately, I provide the additional link 26, which connects the link- 25 engaging end of one of the clamps with the link-engaging end of the opposite lever 22. It will be seen that with this construction, one of the handles will be swung inwardly while the other is being moved outwardly, 30 so that the clamps 16 will be alternately engaged with the friction disk, and a smoother movement of the frame gained.

In the drawings as disclosed, I have shown only two clamping members with 35 their respective leverage, but it will be understood that as many clamps may be provided as there are seats, if so desired. In a device of this kind in which there are merely four seats provided, it has been 40 found sufficient to provide but two propelling clamps, and it may be stated that one occupant may propel the device by the use of only one lever, as the leverage is such as to give great power with slight manual op- 45 eration.

From the foregoing, it will be seen that I have provided a device having a frame revoluble on a mast, and adapted to be propelled by means of frictional devices oper- 50 ated by persons carried on the frame. It will still further be seen that I have pro- 55 vided an improved friction means for the propulsion of my device comprising a sta- tionary disk and friction clamps adapted to be forced into engagement therewith. It will still further be seen that I have pro- 60 vided a device of this character which consists of few working parts, and which is practically inexpensive to manufacture. It 65 will still further be seen that by providing the connecting link 26, as hereabove de- scribed, the clamps will be alternately en- gaged with the friction disks, so that the lever 24 may be effectively operated, both in its outward and its inward movement

from and to the seat, respectively. Hence it will be seen that one person may operate the device effectively.

What I claim is:

1. A device of the character described, comprising a fixed base, a mast thereon, a frame revolubly mounted on said mast, a disk fixedly mounted on said mast, levers carried by said frame, clamping members also carried by the frame in a position in close proximity to said disk, links connect- 75 ing each clamp with a lever, and an additional link connecting one of said clamps with the opposed lever, whereby said clamps may be alternately forced into frictional en- 80 gagement with said disk to revolve the frame on said mast.

2. A device of the character described, comprising the combination with a fixed base, a mast thereon, a frame carrying 85 seats thereon revolubly mounted on said mast, a circular plate carried by the frame through which said mast extends and a disk fixed on said mast provided with a depend- 90 ing flange, said disk being spaced a short 95 distance above said plate; of clamping mem- bers resting on said plate provided with slots to receive the depending flange of the disk, operating means carried by the frame and disposed adjacent the seats for forcing 100 the clamps into frictional engagement with the disk, and additional means connecting the operating means of the respective clamps, whereby the effective engagement of the clamps with the disk will be alter- 105 nate.

3. In a device of the character described, the combination with a fixed base, a mast thereon, a frame revolubly mounted on said mast, said frame being provided with a cir- 105 cular plate through which said mast ex- tends and a disk fixed on said mast and spaced a short distance above said plate, said disk being provided with an annular depend- 110 ing flange; of a pair of clamping 110 members resting on said plate provided with slots to receive the annular flange of said disk, the walls of said slots being serrated to provide effective engaging faces, plates removably engaged with said clamping 115 members and contacting with the upper face of said disk to retain said clamping mem- bers in position thereagainst, and means carried on said frame for alternately forc- 120 ing the engaging faces of said clamping members into frictional engagement with the flange of said disk.

4. In a device of the character described, the combination with a fixed base, a mast thereon, a frame revolubly mounted on said mast and a disk fixed on said mast; of a pair of clamping members carried by the frame and adapted to revolve with the frame about said disk, a pair of levers mounted on said frame at diametrically opposite points 125 130

thereon, a link connecting each of said clamping members with a lever, and an additional linking member connecting one of said clamping members with the lever of the opposed clamping member, whereby the

5 levers may only be operated alternately to force the clamping members into frictional engagement with the disk.

In testimony whereof I hereunto affix my signature in the presence of two witnesses.

LAWSON B. STEWART.
